His Attorney.

UNITED STATES PATENT OFFICE

GEORGE PAILIN, OF MANCHESTER, ENGLAND, ASSIGNOR TO GENERAL ELECTRIC COMPANY, A CORPORATION OF NEW YORK

ELECTRIC SWITCH GEAR.

Application filed October 19, 1929, Serial No. 400,988, and in Great Britain January 9, 1929. Renewed March 11, 1932.

My invention relates to the truck or draw-out type of electric switchgear wherein means for breaking the electric circuit is incorporated in the withdrawable or movable portion of the switchgear.

In switchgear of the aforesaid type the electrical connection between the withdrawable portion and the live contacts or busbars of the stationary portion is usually made by 10 plugs and sockets of a type which allow for slight variations in the circuit closing position of the withdrawable portion without affecting the electrical connection. For heavy currents, it is important that sufficient pressure between the plugs and sockets shall exist 15 in order to ensure efficient electrical connection, but this pressure must not interfere with or hinder the operation of readily making and breaking the electrical connection 20 between the withdrawable and fixed portions of the switchgear. The withdrawable portion may comprise a circuit breaker, a switch, 25 switch fuse, a transformer and switch or other arrangements involving apparatus for making and breaking electric circuits, and such may be of the oil, air or other types.

A principal object of my invention is the provision of means incorporated in the co-operating electrical contacts of the fixed and 30 movable portions of the switchgear for increasing the pressure between the coacting contacting surfaces to insure efficient electrical contact when the movable portion is in its circuit closing position, and for decreasing 35 the aforesaid pressure in response to movement of the movable or withdrawable portion towards its open circuit position, thereby facilitating withdrawal thereof.

In accordance with my invention, the 40 switch or circuit breaker mounted upon the withdrawable portion of the switchgear when operated to close the circuit imposes pressure, by means of a member actuated by the switch, between the electrical contacts 45 which connect the withdrawable and stationary parts of the switchgear so that good electrical connection between said parts is ensured by the act of closing the switch.

Further, in accordance with another aspect 50 of my invention the switch when operated to

break the circuit, releases the pressure between the aforesaid contacts, so facilitating the withdrawal of the contacts from engagement with each other. With the aforesaid arrangement, it will be apparent that pressure sufficient to ensure good electrical connection is applied only between the electrical contacts when it is required, that is, when the electrical circuit is completed.

My invention will be more fully set forth 55 in the following description referring to the accompanying drawings, and the features of novelty which characterize my invention will be pointed out with particularity in the 60 claims annexed to and forming a part of this 65 specification.

Referring to the accompanying drawings, Figs. 1 and 2 are elevational sectional views 70 of switchgear embodying my invention wherein the means for breaking the electric 75 circuit between the withdrawable portion and the live contacts are illustrated in the open and closed circuit positions respectively, and Fig. 3 is a cross-sectional view taken on the line A—B of Fig. 1.

In the illustrated application of my invention to the draw-out type of switchgear, in which plug and socket electric connections are employed between the withdrawable and fixed parts, the plug or equivalent member 1 is split or divided at one end into a number of segments 2, the end of the plug so divided entering within a solid socket 3. Within the end of the plug disposed within the socket 3 are arranged two wedge shaped members, as the cones 4 and 5 with their apices adjacent each other, or together as illustrated. The cones 4 and 5 are mounted upon a central stem or sleeve 6, the cone 4 being fixed to the sleeve 6 and the cone 5 being freely slidable thereon. The annular space between the outer surfaces of the cones and the internal surface of the plug is filled with suitable pressure-transmitting material, as the balls 7. The cone 5 which is slidably 80 mounted upon the sleeve 6 is pressed towards the cone 4 by a resilient member, as the spring 8 disposed around the sleeve. One end of the spring bears upon a collar 9 seated upon a key-like element 10 extending trans- 85

versely of the sleeve and through slots 10a therein so that the key may move longitudinally with respect to the sleeve. Such longitudinal movement is effected by a member, as 5 the rod 11, which passes centrally of and through the plug to a position where it is adapted to be engaged by the cross bar 12 of the switch when such bar is in the circuit closing position, as illustrated in Fig. 2.

- 10 When therefore the switch is closed, pressure is applied through the rod 11 and spring 8 to the movable cone 5 and so to the pressure-transmitting material or balls within the plug segments. The balls accordingly trans- 15 mit this pressure so as to apply an even expansive or radial pressure to the segments 2 of the plug, thereby forcing them into firm contacting engagement with the contacting surface of socket 3 to insure the desired good 20 electrical contact between the plug and socket.

When the switch is opened the cross bar 12 is moved downwardly and the spring pressure applied through the bar 12 and rod 11 is removed from the movable cone 5 and the 25 balls 7, thereby releasing the pressure on the plug segments. Accordingly, the withdrawal of the plug from the socket may be readily effected without difficulty.

It will be seen that with my improvement, 30 the plugs and sockets of truck-type switchgear are moved into or out of engagement as readily as with the ordinary types of plugs and sockets with the added advantage that when the circuit through the same is completed, a sufficient additional pressure is applied between the said parts to ensure the desired electrical connection to carry comparatively heavy currents in a satisfactory manner. Furthermore, it will be noted that the 35 pressure exerted to apply the pressure between the fixed and withdrawable contacts comprising the plug and socket is effective through rod 11 to assist in opening the switch 12, thereby accelerating the speed of breaking the circuit. A greater pressure between the electrical contacts during the circuit closing position is exerted than could reasonably be obtained with the present known types of 40 plug and socket contacts.

45 The compressible and expandible plug per se and the means for varying the pressure between the plug and its socket are not claimed herein apart from the combination thereof with the switch member; said plug and means 50 for varying the pressure between the plug and its socket are the subject matter of my application Serial No. 400,987, filed October 19, 1929, concurrently herewith.

What I claim as new and desire to secure 60 by Letters Patent of the United States, is,—

1. In electrical switchgear of the draw-out type, contact structure comprising a stationary member and a movable member adapted to engage and electrically contact 65 with said stationary member, a switch mem-

ber coacting with the aforesaid contact structure, and means actuated by said switch member in accordance with its circuit controlling position for varying the contact pressure between said stationary and movable members. 70

2. In electrical switchgear of the draw-out type, a stationary contact, a movable withdrawable portion comprising a contact member for coacting with said stationary contact, a switch member carried by said withdrawable portion, and means actuated by said switch member in accordance with its circuit controlling position for affecting the contact pressure between the aforesaid 75 contacts. 80

3. In electrical switchgear of the draw-out type, a stationary contact, a movable withdrawable portion comprising a contact adapted to coact with and engage said stationary contact, a switch carried by said withdrawable portion adapted to be closed after the aforesaid contacts are in engagement, and means actuated by the switch for further pressing said contacts into engagement with 85 each other. 90

4. In electrical switchgear of the draw-out type, a stationary socket contact, a movable withdrawable portion comprising a coacting plug contact, a switch member carried by 95 said withdrawable portion, and a member reciprocally mounted with respect to said plug contact adapted to be actuated by said switch member in accordance with a circuit controlling position of said member for increasing the contact pressure between said 100 plug and socket contacts. 105

5. In electrical switchgear of the draw-out type, a withdrawable portion comprising a switch for interrupting the circuit between the live and withdrawable portions, plug and socket contacts adapted to be engaged and disengaged by movement of the withdrawable portion, and wedging means for increasing the contact pressure between the 110 plug and socket contacts actuated by the aforesaid switch in response to circuit closing movement thereof. 115

6. In electrical switchgear of the draw-out type comprising plug and socket connections, a withdrawable portion with respect to which a plug contact is mounted, a switch likewise mounted with respect to said withdrawable portion, wedging means disposed centrally of the plug contact and adjacent its contacting end, and means actuated by said switch during closure thereof for moving said wedging means to cause expansion of the contacting end of the plug thereby effecting good contacting engagement with 120 its coacting socket connection. 125

7. The combination with truck type electrical switchgear comprising stationary and withdrawable portions, of electrical contacting structure comprising a socket connection 130

mounted with respect to the stationary portion, a coacting plug connection mounted with respect to the withdrawable portion, a switch for interrupting the circuit between the stationary and withdrawable portions, and means responsive to a circuit controlling position of said switch for effecting expansion of the contacting end of said plug, thereby increasing the contact pressure between the plug and its coacting socket.

8. The combination with truck type electrical switchgear comprising stationary and withdrawable portions, of electrical contacting structure comprising a socket connection mounted with respect to the stationary portion, a hollow plug connection mounted with respect to the withdrawable portion, a switch likewise mounted with respect to the withdrawable portion for interrupting the circuit between the stationary and withdrawable portions, wedging means disposed centrally of and within said plug connection and adjacent its contacting end, said wedging means resiliently biased to exert expansive pressure at the contacting end of said plug for increasing the contact pressure between said plug and socket connections, and means for exerting additional bias on said wedging means to increase the aforesaid pressure in response to closing movement of said switch.

9. The combination with truck type electrical switchgear comprising stationary and withdrawable portions, of electrical contact structure comprising a stationary socket member, a coacting plug member mounted on the withdrawable portion, a switch for interrupting the circuit between the stationary and withdrawable portions, resiliently biased means for effecting expansion of the contacting end of said plug member, thereby increasing the contact pressure between the same and said socket member, and means responsive to the circuit closing movement of said switch for further increasing the aforesaid contact pressure, said last-named means being resiliently biased to assist in accelerating the opening movement of the switch.

10. The combination with truck type electrical switchgear comprising stationary and withdrawable portions, of electrical contact structure comprising a socket member mounted on the stationary portion, a hollow plug member mounted on the withdrawable portion, a switch for interrupting the circuit between the stationary and withdrawable portions likewise mounted on the withdrawable portion, wedging means disposed within the contacting end of said plug and adapted to effect expansion of that end of the plug for ensuring good contacting engagement with the coacting socket member, resilient means for normally biasing said wedging means into pressure-transmitting engagement with the contacting end of said plug, and a member actuated by said switch during move-

ment thereof to its circuit closing position for further increasing the pressure of said resilient means to effect firm contacting engagement between said plug and socket members, said last-named member adapted to relieve 70 said added pressure upon opening movement of the switch prior to the separating movement of the plug and socket members.

11. In electrical switchgear of the draw-out type, a stationary contact, a movable withdrawable portion comprising a contact member for coacting with said stationary contact, a switch member carried by said withdrawable portion, and means responsive to opening movement of said switch member 75 prior to separation of said contacts for decreasing the pressure between said contacts, thereby facilitating separation thereof.

12. In electrical switchgear of the draw-out type, a stationary socket contact, a movable withdrawable portion comprising a plug contact for coacting with said stationary contact, a switch member carried by said withdrawable portion, and pressure controlling means responsive to opening movement of 80 said switch member prior to separation of said plug and socket contacts for decreasing the pressure therebetween so as to facilitate withdrawal of the plug from the socket.

13. In electrical switchgear of the draw-out type, a stationary contact, a withdrawable portion comprising a movable contact member for coacting with said stationary contact, a switch carried by said withdrawable portion, and means coacting with said switch for increasing the pressure between the coacting contacting surfaces of said stationary and movable contacts when said switch is in its circuit closing position, and for decreasing the aforesaid pressure in response to opening of said switch thereby facilitating withdrawal of said portion.

In witness whereof, I have hereunto set my hand this 4th day of October, 1929.
